UNITED STATES PATENT OFFICE
2,381,899
EXPANSION REAMER
James H. Gracey, Springfield, Mass.

Application August 21, 1943, Serial No. 499,441
3 Claims. (Cl. 77—76)

(Granted under the act of March 3, 1883, as
amended April 30, 1928; 370 O. G. 757)

The invention described herein may be manufactured and used by or for the Government for governmental purposes without the payment to me of any royalty thereon.

This invention relates to an adjustable expansion reamer.

The finish reaming of a hole to provide an exceptionally smooth finish requires a specially ground reamer. Such a reamer is generally made from a conveniently fluted reamer. Each end of the reamer is however tapered toward the middle so that a small central portion of the reamer is of slightly larger diameter than the ends. Thus the enlarged portion of the reamer does the actual cutting. A reamer of this type is commonly used for the final finish reaming of rifle bores to ream such bore to within very close tolerance limits and to provide a highly finished interior surface.

The taper produced on such a reamer is however very slight so that the center section of the reamer is only two or three ten thousandths of an inch larger in diameter than the ends thereof. It is therefore quite apparent that grinding such a taper is an exacting procedure. It is also evident that when the enlarged center portion of the reamer wears down such reamer will no longer be satisfactory for use and must be discarded. In the past reamers of this type have been made with integral shanks which add appreciably to the cost of the reamer. Obviously such shanks are also lost when the reamers are of no further use. In addition lubrication of the cutting edges of these reamers has been left more or less to chance.

It would therefore be desirable to provide a reamer which could be cylindrically ground and then simply expand the center portion sufficiently to provide the desirable enlarged center portion for a smooth cutting scrape reamer. In addition a reamer provided with a readily removable shank in which is incorporated positive means for thorough distribution of lubricating oil about the periphery of the reamer would also be most desirable.

A particular object of this invention is to provide a reamer having readily adjustable means for expanding such reamer any desired amount within the elastic limit of the reamer steel.

Another object of this invention is to provide a readily removable shank for a reamer for the purpose of reducing breakage of the reamer and to effect a saving of reamer steel.

Still another object of this invention is to pro-

vide adequate oil distribution for positive lubrication of the reamer.

The specific nature of the invention as well as other objects and advantages thereof will clearly appear from a description of a preferred embodiment as shown in the accompanying drawing in which:

Fig. 1 is a side elevational view of the assembled reamer.

Fig. 2 is a right end elevational view of Fig. 1.

Fig. 3 is a longitudinal sectional view of Fig. 1.

Fig. 4 is a cross sectional view taken along the plane 4—4 of Fig. 3.

Fig. 5 is a partial longitudinal sectional view of Fig. 1 taken along the plane 3—3 of Fig. 4 showing the lubricating oil passages in the adapter.

The reamer to be described in more detail later takes advantage of the elasticity of the steel from which the reamer is fabricated. Briefly the reamer is expanded by an expander member including a tapered plug insertable in a tapered axial hole within the central portion of the reamer. By advancing the tapered plug into the tapered hole by a screw which may or may not be integral with the tapered plug, the center portion of the reamer may then be expanded any desired amount within the elastic limit of the steel utilized. A threaded adapter is inserted in one end of the reamer in place of the usual integral shank. A reamer rod is then screwed onto the other end of the adapter. A washer placed between the reamer and the adapter breaks up the flow of oil coming from the reamer rod and sprays it evenly around the flutes of the reamer thereby insuring positive lubrication.

There is shown in Figs. 1 and 2 in assembled relation the expansion reamer embodying this invention. A straight fluted reamer 1 is connected to a reamer tube 2 by means of an adapter 3. The exterior of reamer 1 as shown in the accompanying figures resembles a conventional cylindrically ground fluted reamer. Reamer 1, however, is provided with an axial hole 4. The right end of axial hole 4 as viewed in Fig. 3 is counterbored to within a short distance from the center of reamer 1 to provide an enlarged hole 5. A tapered portion 6 is provided from the bottom of hole 5 to hole 4 which extends a short distance beyond the center of reamer 1. The plug part 7 of the expander will have a taper corresponding to that of tapered portion 6 and is for insertion through hole 5 and into tapered portion 6. Counterbored hole 5 is provided with threads 8 to receive the expanding screw portion 9 of the ex-

pander and a locking screw 10, as shown. The left end of axial hole 4 is counterbored and threaded to form an enlarged portion 11 of hole 4 to receive a threaded end 12 of an adapter 3.

Adapter 3 is a cylindrical member provided with two threaded ends 12 and 13 of reduced diameter. Two oppositely disposed slots 14 and 15 are provided in adapter 3 to provide a passage for the lubricating oil which is forced under pressure in a conventional manner through the hollow interior of a reamer tube 2 for the purpose of lubricating reamer 1. A washer 16 is placed around the reduced diameter end 12 of adapter 3 and adjacent reamer 1. Thus the washer 16 blocks the oil passages 14 and 15 and forces the oil to be diverted in a manner to be described in more detail later.

The reamer is readily expanded and adjusted for cutting by turning screw part 9 against tapered plug part 7. The pressure brought against part 7 by the threading of part 9 forces the walls of the reamer to expand outwardly about tapered portion 6 of hole 4. The amount of expansion necessary for a reamer utilized, for example, in finish reaming rifle barrels need be but two or three ten thousandths of an inch. This amount may be measured by a micrometer or preferably by a ring gage. When the reamer has been expanded at its center section to the required diameter the lock screw 10 is then screwed into threads 8 to bear tightly against screw 9 thereby locking screw 9 securely in place. The adapter 3 is then screwed into the left end of reamer 1 as viewed in Figs. 1 and 3 with the washer 16 placed between the two. The end 13 of adapter 3 is then screwed into the threaded end of a conventional reamer tube 2. The lubricating oil passages 14 and 15 then communicate with the hollow portion 17 of reamer tube 2.

The reamer is now assembled to the reamer tube 2 and is ready for finish reaming a bore. When the reamer is inserted in the bore and set in motion the reamer will cut only on the enlarged central portion that has been expanded by the tapered plug 7. Lubricating oil is then admitted to the hollow portion 17 of reamer tube 2 from a suitable oil source (not shown). The oil should be supplied under pressure so that it is readily forced into the passages 14 and 15 of the adapter 3. Upon striking washer 16 the oil is directed outwardly, spraying out in a fanlike direction thereby positively insuring the lubrication of the cutting edges of the reamer. As the two oil passages 14 and 15 are oppositely disposed to one another each spray will cover 180° of the circumference of the reamer and will therefore insure complete and positive lubrication of all the cutting blades.

It is desired to point out that by providing an adapter 3 the usual integral shank generally provided on one end of the reamer may be eliminated thereby effecting a considerable saving in the cost of the reamer. The adapter 3 may be readily made on a screw machine and may be made of less expensive material than the high quality tool steel employed in the fabrication of the reamers. It is readily apparent that if the adapter 3 be made of comparatively soft material such adapter would yield before reamer 1 in the event the reamer should stick in the barrel

and thus prevent damage to the reamer. As the adapter 3 is cheaply replaced considerable further saving would thereby be effected.

It is desired to point out that the reamer described herein is preferably used for finish reaming the bore of a firearm barrel but such reamer is not necessarily limited to this application. It is further desired to point out that the amount of expansion obtainable by such a reamer is limited only by the elastic limit of the material from which the reamer is made. Normally, however, the amount of expansion desired is a relatively small amount so that there is little if any danger of ever exceeding the elastic limit of the reamer material.

I claim:

1. In a tool of the kind described, in combination with a longitudinally-bored body having exterior cutting surfaces, a threaded portion at each end of the bore and an intermediate tapering portion, an expanding member including an externally tapered part at one end and an externally threaded part at its other end, said threaded part of the expanding member engaging one threaded portion of the bore and said tapered part engaging said tapering portion of the bore, a shank having a threaded portion engaging the other threaded portion of the bore, said shank being provided with a longitudinal lubricant groove therein, and a lubricant dispersion member mounted on said shank adjacent said body.

2. In a tool of the kind described, in combination with a longitudinally-bored body having exterior cutting surfaces, a threaded portion at each end of the bore and an intermediate tapering portion, an expanding member including an externally tapered part at one end and an externally threaded part at its other end, said threaded part of the expanding member engaging one threaded portion of the bore and said tapered part engaging said tapering portion of the bore, a shank having a reduced diameter threaded portion engaging the other threaded portion of the bore, said shank being provided with longitudinal lubricant grooves therein, and a washer mounted on said reduced diameter threaded portion of said shank adjacent said bore, said washer abutting the ends of said lubricant grooves whereby said washer operates as a lubricant-dispersion member.

3. In a tool of the kind described, in combination with a longitudinally-bored body having exterior cutting surfaces, a threaded portion at each end of the bore and an intermediate tapering portion, an expanding member including an externally tapered part at one end and an externally threaded part at its other end, said threaded part of the expanding member engaging one threaded portion of the bore and said tapered part engaging said tapering portion of the bore, a reamer tube having an internally threaded bore, an adapter member having one end portion threadably engaging the other threaded portion of the bore of the body and its other end portion threadably engaging the bore of the reamer tube, said adapter member being provided with a longitudinal lubricant groove therein, and a lubricant dispersion member mounted on said adapter member closely adjacent said body.

JAMES H. GRACEY.
